Patented Apr. 8, 1975

234,814

HORIZONTAL TRASH COMPACTOR

Lewis P. White, 3436 Brookwood Road,
Birmingham, Ala. 35223

Filed Apr. 11, 1972, Ser. No. 243,113

Term of patent 7 years

Int. Cl. D15—09

U.S. Cl. D55—1 B

Fig. 1

Fig. 2

Fig. 3

Fig. 5

Fig. 4

FIG. 1 is a side elevational view of a horizontal trash compactor, showing my new design;

FIG. 2 is a top plan view thereof;

FIG. 3 is a bottom plan view thereof;

FIG. 4 is a left end elevational view thereof; and

FIG. 5 is a right end elevational view thereof.

The side opposite the side shown in FIG. 1 is identical thereto.

I claim:

The ornamental design for a horizontal trash compactor, as shown and described.
